UNITED STATES PATENT OFFICE.

WILHELM WANDERER, OF NEWARK, NEW JERSEY.

DESIGN FOR A LADLE-HOLDER.

SPECIFICATION forming part of Design No. 24,378, dated June 11, 1895.

Application filed May 10, 1895, Serial No. 548,873. Term of patent 3½ years.

To all whom it may concern:

Be it known that I, WILHELM WANDERER, a citizen of the United States, residing at Newark, in the county of Essex and State of New Jersey, have invented a new and original Design for a Ladle-Holder, of which the following is a specification.

This invention relates to a new and original design for ladle holders; and it has for its object to provide a design of this character that shall be both useful and ornamental.

The leading feature of the design resides in a horizontal substantially rectangular body provided with curved or rounded front corners to form a D-shaped figure having within the plane of its upper surface a series of small circular figures.

Another feature of the design resides in providing said rectangularly shaped body with a vertically disposed portion arising from one side thereof and having a pair of semi-elliptical lobes bounded by sigmoidal-shaped lines merging together at a central point to form a V-shaped figure between the lobes.

In the drawings, Figure 1 is a perspective view of a ladle-holder embodying the herein-

described design. Fig. 2 is a plan view thereof. Fig. 3 is a front view thereof.

Referring particularly to the drawings, the numeral 1 designates a substantially rectangular body provided with curved or rounded front corners 2, to form a D-shaped figure. The body 1, is also provided within the plane of its upper surface with a series of small circular figures 3, and at one side edge with a vertically disposed portion 4. The vertically disposed portion 4, of the body is provided with a pair of semi-elliptical lobes 5, bounded by sigmoidal lines 6, which lines merge together at a central point as at 7, thereby forming a re-entrant angle or V-shaped figure 8.

What I claim is—

The design for a ladle holder herein shown and described.

In testimony that I claim the foregoing as my own I have hereto affixed my signature in the presence of two witnesses.

WILHELM WANDERER.
